CLAIM

The ornamental design for a bin as shown and described.

DESCRIPTION

FIG. 1 is a top front perspective view of a bin, according to the new design.

FIG. 2 is a bottom front perspective view of the bin shown in FIG. 1.

FIG. 3 is a top rear perspective view of the bin shown in FIG. 1.

FIG. 4 is a bottom rear perspective view of the bin shown in FIG. 1.

FIG. 5 is a front elevation view of the bin shown in FIG. 1.

FIG. 6 is a rear elevation view of the bin shown in FIG. 1.

FIG. 7 is a left side elevation view of the bin shown in FIG. 1.

FIG. 8 is a right side elevation view of the bin shown in FIG. 1.

FIG. 9 is a top plan view of the bin shown in FIG. 1; and, FIG. 10 is a bottom plan view of the bin shown in FIG. 1. The broken lines in the drawings illustrate portions of the bin that form no part of the claimed design.

1 Claim, 10 Drawing Sheets
